UNITED STATES PATENT OFFICE.

DAVID C. SASSEMAN, OF RIVER FOREST, ILLINOIS, ASSIGNOR TO F. H. SMITH MANUFACTURING COMPANY, OF CHICAGO, ILLINOIS, A CORPORATION OF ILLINOIS.

SEAL PRESS.

Application filed August 31, 1925. Serial No. 53,453.

The purpose of this invention is to provide an improved and simplified construction of a seal press adapted to be constructed of metal stampings and affording convenience for withdrawing the seal member for rectifying or replacing the seal elements. It consists in the elements and features of construction shown and described as indicated in the claims.

10 In the drawings:

Figure 1 is a perspective view of a completely assembled seal press embodying this invention.

15 Figure 2 is a perspective view of the three principal stamped metal parts of the seal press, dissected.

Figure 3 is a medial longitudinal vertical section of the press showing the die members in elevation.

20 Figure 4 is a side elevation of the removable die carrier, removed from the press.

The seal press shown in the drawings comprises three principal elements, each of which is a metal stamping, viz., a base member, A, standard, B, and operating lever, C. The base member is substantially flat with a central longitudinal part struck up, as seen at A¹, leaving a marginal portion, A², for resting upon a flat support, said up-struck central longitudinal portion, A¹, affording seat for the standard, B, which is formed from a sheet metal blank folded at parallel lines to produce a channel member open from end to end, and with the sides,

35 B¹, B², parallel, and the connecting web, B², dimensioned for seating upon the up-struck central longitudinal area, A¹, of the base member to which said standard is secured rigidly by any convenient means, preferably 40 spot welding. The standard member is given the form of a pair of rigid jaws by deep notches, B³, cut in from the forward end in both of the upright sides, said notches being registered or aligned with each other

45 horizontally. The operating lever member, C, is struck from a metal blank forming a downwardly-open, upwardly-curved channel for the handle or longer arm, C¹, from which extend parallel lugs, C², C², constituting the shorter arm of the lever, and between which at their extremities there is mounted a cam roll, 10. This operating lever is mounted between the parallel sides

of the channel standard, pivoted thereto at the upper forward corner by a pivot bolt, D. 55

The press comprises, beside the three metal stamping parts mentioned and described, the seal carrier which consists of two flat bars, 12 and 13, pivoted together at one end, and at the opposite ends enlarged as seen at 12^a, 13^a, for carrying the co-operating die enclosing cups, 20 and 21, which are spot-welded or otherwise equivalently permanently secured to said enlargements 60 respectively with their cavities facing each other. Coiled around the pivot of the two bars, 12 and 13, at their pivoted end is a spring, 15, which reacts upon the two bars for holding them normally spread apart at the seal-carrying ends. The bars, 12 and 13, throughout their length back of the enlargement, 12^a, 13^a, are of width to enter and fit quite closely between the parallel upright sides of the channel standard 65 70 bracket, B; and the facing edges of the rigid jaws formed by the notches, B³, are recessed or notched at their upper and lower edges respectively, as seen at 17, 17, and 18, 18, to engage and thereby definitely position the enlargements, 12^a, 13^a, when the seal carrier has been thrust in from the forward end of the standard entering the seal carrier enlargements with the cups thereon between the upper and lower jaws; and when thus 75 entered the reaction of the spring, 15, holds 80 the enlargements, 12^a, 13^a, safely in the notches, 17, and 18, respectively.

In detail the construction of the bars, 12 and 13, for pivoting together at their rear ends is that the blanks from which they are 90 formed have transversely projecting lugs, 12^b, 12^b, and 13^b, 13^b, which are folded at right angles to their original plane, the lugs of one jaw,—the upper jaw, 12,—being folded so as to be spaced narrowly enough to 95 enter between the more widely folded lugs, 13^b, of the lower jaw, as seen in Figure 3, and the spring, 15, is coiled on the pivot between the more narrowly folded lugs of the upper jaw. For stopping the operating lever at a proper upward limit of swing of the handle arm, a pin, 25, is set through the vertical sides of the channel standard extending across the channel at a position to be 100 encountered by the short arm of the lever at 105 the position to which it will be forced by the

reaction of the spring, 15, spreading arms of the die carrier to seat the upper die-carrying enlargement, 12^a, against the lower edge of the upper jaw,—that is, at open or separated position of the die members.

I claim:

1. A seal press and the like comprising a hollow rigid jawed open front and open top standard; a bell crank lever comprising a longer and a shorter arm fulcrumed in the upper part of the standard with the longer arm extending out through the open top and the shorter arm depending in the cavity of the standard normally trending back from the fulcrum; a seal carrier comprising two equal bars hinged together at one end and enlarged at the opposite end for carrying respectively the co-operating seal members, and a spring reacting about their pivot for holding the seal carrier enlargement normally spread apart; said seal carrier being dimensioned as to width of the bars back of the enlargements for entering the open front of the standard and fitting in the horizontal width of the cavity, said enlargement being dimensioned for entering between the rigid jaws, said jaws having notched recesses for seating the enlargements respectively.
2. A seal press and the like comprising a standard consisting of a base and parallel up-standing brackets made rigid with the base and deeply notched at their forward ends to form forwardly-open rigid jaws; an operating lever fulcrumed between the brackets at their upper part having an arm depending from the fulcrum; a seal carrier comprising a pair of arms hinged together

at one end and at the other end enlarged and adapted for mounting co-operating seal members, said arms back of said enlargement being adapted to be entered and to fit between the standards; said standards having means for engaging the seal enlargements to position the seal carriers in the standards.

3. In a seal press and the like, a standard for seal members and operating means, comprising a base, and an upright mounted on the base and adapted for mounting on it a fixed seal member and the like, said upright consisting of a unitary member of upwardly open channel form, the channel extending the entire length of said member and from its upper open edge to a depth below the mounted position of the fixed seal member having its sides upright and parallel and the bottom web seated on and secured rigidly to the base.

4. In the construction defined in claim 3, the channel sides being notched at their forward edges for admitting seal members and the like, and being extended longitudinally and upwardly from the back of the notch to afford rigidity compensating for the weakening by the notches, and an operating handle pivoted between the channel sides at the upper forward corner of the notched end, adapted to fold down between the channel sides throughout the entire horizontal length of the latter.

In testimony whereof, I have hereunto set my hand at Chicago, Illinois, this 25th day of August, 1925.

DAVID C. SASSEMAN.
